VARIABLE RESISTANCE DEVICE

Marion J. Arvin, Indianapolis, Ind., assignor to
 P. R. Mallory & Co., Inc., Indianapolis, Ind., a
 corporation of Delaware

Application October 31, 1936, Serial No. 108,588

5 Claims. (Cl. 201—63)

This invention relates to resistance devices and more particularly to variable devices comprising an arcuate resistance element and a moving contact therefor.

5 An object of the present invention is to improve the construction of such devices.

Other objects of the invention will be apparent from the following description and accompanying drawing taken in connection with the appended 10 claims.

The invention comprises the features of construction, combination of elements, arrangement of parts, and methods of manufacture and operation referred to above or which will be brought 15 out and exemplified in the disclosure hereinafter set forth, including the illustrations in the drawing.

In the drawing:

Figure 1 is a face view of a variable resistance 20 device embodying one form of the present invention;

Figure 2 is a section on the line 2—2 of Figure 1, and

Figure 3 is a perspective view of a spring wedge 25 for said device.

While a preferred embodiment of the invention is described herein, it is contemplated that considerable variation may be made in the method of procedure and the construction of parts 30 without departing from the spirit of the invention. In the following description and in the claims, parts will be identified by specific names for convenience, but they are intended to be as generic in their application to similar parts as 35 the art will permit.

In variable resistance devices, rheostats or potentiometers, particularly those comprising a winding of resistance wire, such as are used for volume controls in radio sets, the resistance element is commonly enclosed within a cylindrical casing. It is a common practice, for example, to wind the resistance wire on a strip of insulating material, such as uncured Bakelite fibre, which is then bent into a circular shape to conform to the inside wall of a cup or housing. Since 45 the housing is usually formed of metal, it is necessary to provide a lining of insulating material between the wall of the housing and the circular resistance element. It is also necessary to secure the element within the housing in some positive manner so that it will not become loose during operation or after long periods of time. Various methods have been used in the past for securing the resistance element within the housing, such 50 as riveting and clamping. These methods are

relatively costly and it is necessary to shape the terminals so that they will clamp positively on the ends of the resistance element. The use of a solid wedge between the ends of the strip of insulating material is unsatisfactory because of 5 loosening as a result of heating or drying out of the insulating strip, with a resultant tendency toward shrinkage.

In accordance with the present invention a positive permanent anchoring means is provided 10 for the resistance element comprising a spring member interposed between the ends of the element so as to hold the parts together under compression at all times.

Referring to the drawing, Figure 1 shows a 15 face view of a variable resistance device 10, with the cover removed and Figure 2 shows a section through this device showing the details of the improved spring wedge arrangement of the present invention. The device 10 comprises a 20 metal shell or cup 11 having a cylindrical side wall 12 and a flat end wall 13. Disposed within shell 11 and resting against the walls thereof are lining members of sheet insulating material, such as sheet Bakelite, one of said members comprising a disc 14 disposed against end wall 13 and the other of said members comprising a cylindrical strip 15 disposed against the cylindrical wall 12 of the cup.

The resistance element 16, comprising a resistance wire 17 wound on a Bakelite strip 18, is 30 bent into generally cylindrical shape so as to fit within cup 11 with its outer surface against lining member 15 and one of its edges against lining member 14. A pair of terminal lugs 19 and 20 35 pass through openings 21 and 22 in wall 12 of the cup and through openings in lining member 15, the inner ends of lugs 19 and 20 making electrical connection with the respective ends of the resistance winding 17. A third terminal lug 23 40 passes through the wall of the cup and between the ends 24 and 25 of strip 18 and connects to rotatable contact member 26 in the center of the cup. Member 26 carries a sliding contact portion 27 which slides along the free edge of resistance winding 17 for varying the resistance 45 of the device.

In order to hold the resistance element securely in place at all times, spring wedge 28 (see Fig. 3) is inserted between the ends 24 and 25 of strip 18. 50 Spring wedge 28 comprises a U-shaped piece of spring metal, such as bronze or the like. The wedge 28 is preferably formed with small projections 29 and 30 on the outside edges of the arms of the U, at the ends thereof, which pro- 55

jections become embedded in the ends of strip 18 when the spring wedge is forced into position. Projections 29 and 30 may merely comprise the burr, incident to shearing the metal used to form the U-shaped spring element.

Since strip 18 is commonly formed of Bakelite or some other synthetic resin material or resin-impregnated fibres, it may have a tendency to shrink upon heating or drying out. The spring wedge 28 is inserted between the ends of the element under compression so that it applies a constant expanding force to the element 18, thereby tending to hold the entire element securely against the wall of the well. Should the element shrink at any time during its life, the spring wedge will expand and remain pressed firmly against the ends so as to maintain the element securely wedged within the case at all times.

With this arrangement, it may, in some instances, be unnecessary to form a special connection between terminals 19 and 20 and the wire of the resistance element since the pressure of the spring wedge will normally be sufficient to hold the ends of the resistance winding firmly against the terminal members.

While the present invention, as to its objects and advantages, has been described herein as carried out in specific embodiments thereof, it is not desired to be limited thereby but it is intended to cover the invention broadly within the spirit and scope of the appended claims.

I claim:

1. A variable resistance device comprising a cylindrical casing and a resistance element therein, said element comprising a strip of material bent to conform to the cylindrical wall of said casing with the ends thereof spaced apart along the wall of said casing and a U-shaped spring wedge between said ends with the arms thereof disposed in engagement with said ends and held in compression by said ends.

2. The combination with an enclosing cup having a circular wall; of a generally circular resistance unit surrounded by the circular wall of the cup and having adjacent end portions; and a spreading device engaging said end portions and exerting expanding action upon the resistance unit in a circular direction to press the resistance unit against the circular cup wall to hold the resistance unit in assembly with the cup, said spreading device comprising a U-shaped spring wedge inserted between said end portions with the arms thereof in engagement with the end portions and held under compression solely by engagement with said end portions.

3. A variable resistance device comprising an enclosing cup having a cylindrical wall, a resistance unit surrounded by the cylindrical wall of the cup and comprising a strip of sheet insulating material and a winding of resistance wire thereon, said unit being bent into generally cylindrical shape with the ends thereof adjacent each other, and a spreading device engaging said ends and exerting expanding action upon the resistance unit in a circular direction to press the resistance unit against the circular cup wall to hold the resistance unit in assembly with the cup, said spreading device comprising a U-shaped spring wedge with the arms of said wedge disposed along said ends, said wedge being held under compression by engagement with said end portions.

4. A variable resistance device comprising an enclosing cup having a cylindrical wall, a resistance unit surrounded by the cylindrical wall of the cup and comprising a strip of sheet insulating material and a winding of resistance wire thereon, said unit being bent into generally cylindrical shape with the ends thereof adjacent each other, and a spreading device engaging said ends and exerting expanding action upon the resistance unit in a circular direction to press the resistance unit against the circular cup wall to hold the resistance unit in assembly with the cup, said spreading device comprising a U-shaped spring wedge with the arms of said wedge disposed along said ends, said arms having projections embedded in said ends, and said wedge being held under compression by engagement with said end portions.

5. The combination with an enclosing cup having a circular wall, of a generally circular resistance unit surrounded by the circular wall of the cup and having adjacent end portions, said resistance unit having a tendency to shrink with age or change of condition, and a spreading device engaging said end portions and exerting expanding action upon the resistance unit in a circular direction to press the resistance unit against the circular cup wall to hold the resistance unit in assembly with the cup, said spreading device comprising a U-shaped spring wedge inserted between said end portions with the arms thereof in engagement with the end portions and held under compression solely by engagement with said end portions, said spring wedge being under sufficient initial compression to maintain pressure against said ends after shrinkage of said strip of material and without subsequent adjustment.
